DESIGN FOR A DRESS

David E. Gottlieb, New York, N. Y.

Application April 23, 1949, Serial No. 2,225

Term of patent 3½ years

(Cl. D3—26)

To all whom it may concern:

Be it known that I, David E. Gottlieb, a citizen of the United States of America, residing in New York, county of New York, and State of New York, have invented a new, original, and ornamental Design for a Dress, of which the following is a specification, reference being had to the accompanying drawing, forming part thereof,

Fig. 1 is a front view of a dress, showing my new design.

Fig. 2 is a rear view thereof.

I claim:

The ornamental design for a dress, substantially as shown.

DAVID E. GOTTLIEB.
